UNITED STATES PATENT OFFICE.

JENNINGS C. WISE, OF CHARLOTTESVILLE, VIRGINIA.

RAIL-CHAIR.

No. 922,653.

Specification of Letters Patent.

Patented May 25, 1909.

Application filed March 31, 1908. Serial No. 424,354.

To all whom it may concern:

Be it known that I, JENNINGS C. WISE, a citizen of the United States, residing at Charlottesville, in the county of Albemarle, 5 and State of Virginia, have invented certain new and useful Improvements in Rail-Chairs, of which the following is a specification.

My invention relates to rail chairs and its 10 novelty consists in the construction and adaptation of the parts as will be more fully hereinafter pointed out.

The object of my invention is to provide 15 means adapted to prevent the spreading and turning of railroad rails spiked to the ties.

Sometimes plates are spiked to a rail in such a way as to overlap its flanges, but in such case the resistance to the shearing force can only be that due to the cross sectional 20 area of the spikes employed. When the blow is transmitted to the rail by the flange of the wheel of the car it acts in two ways upon the common spike and its action is more marked at curved points on the track than 25 at places where the track is straight. The spike on the outside of the rail tends to shear at the plane of contact between the rail flanges and the spike while the spike on the inside of the rail is subjected to a tensile 30 strain in an upward direction. The first kind of strains frequently repeated gradually force the outer spike away from the rail side- 35 wise, and the second kind of strain tends to pull the inner spike out of the tie. Both 40 of these forces tend to free the rail from the grip of the spike until the action of the rail upon the spikes, when the former is struck by the wheel flange, is that of a hammer and causes the rail to crush into the tie to rupture 45 its fibers and further weaken the engagement between the rail and the tie. As the point of contact of the wheel and rail gradually advance, the unloaded portion of the rail has a tendency to spring upward and this action 50 not only causes roughness of motion in the car passing over the rail, but also aids in loosening the spikes along the rail, because it creates an upward thrust thereon.

The purpose of my invention is to obviate 55 in some measure the disadvantages referred to, and this I do by providing the rail chair hereinafter described which is so constructed that the force of the blow of the wheel flange against the rail is distributed between the 55 spikes on both sides of the rail.

In the drawings, Figure 1 is a perspective view of a portion of a rail mounted upon a tie and provided with my improved chair; Fig. 2 is a perspective of the right plate; Fig. 3 is a perspective of the left plate; Fig. 60 4 is a top plan view of a portion of the rail with the parts of the chair assembled, and Fig. 5 is a bottom plan view of the parts shown in Fig. 4.

In the drawings, 10 represents a portion 65 of a rail, of which 11 is a web and 12 and 13 are the flanges.

14 represents a portion of a tie on which the rail is mounted and to which it is secured.

The rail chair comprises two plates, one 70 of which, for convenience I will call the "right" plate and the other the "left" plate. The right plate 20 consists of a flat shank or base 21 provided at 22 and 23 with apertures to receive the spikes. It is 75 recessed at 24 and 25 to engage with corresponding portions of the flange of the left plate 30 and between the recesses is formed a tongue 26 which engages a corresponding recess 34 in the base of the left plate. It is 80 provided with a lip flange 27 which is bent over to engage with the flange 12 of the rail.

The left plate 30 consists of a flat shank or base 31 provided with apertures 32 and 33 to receive the spikes. It is recessed at 34 to 85 engage with the tongue 26 of the right plate 21. It is provided with a lip flange 37 which is bent over to engage with the flange 13 of the rail and is provided with an upwardly 90 projecting substantially vertical supplemental flange 35 to engage the web 11 of the rail and with a transverse reinforcing rib 36. The spikes 40 in the apertures 22 and 32 engage the flanges 12 and 13 of the rail in the usual manner while the spikes 41 in the apertures 23 and 33 serve to hold the plate shanks 95 31 and 21 to the tie.

When the parts are assembled a portion 28 of the lip flange 27 rests upon the upper surface of the shank 31 of the left plate 30, 100 while the corresponding portion 38 of the lip flange 37 enters the recess 24 of the plate 20 and rests on the tie. When the plates are set in position the right and left plates form in effect a chair for the rail and distribute the 105 load over a larger area of the tie than would the rail itself. The crush of the tie by the impact of the car wheel flange is therefore greatly obviated. It will be observed that the shanks of the plates interlock horizon- 110

tally and that the part 28 of the lip flange 27 resting upon the upper surface of the base plate 31 and each of the lip flanges resting upon the flanges of the rail produce a vertical lock. Therefore, there results a practically perfect vertical and horizontal lock between the parts. When the blow of the wheel flange is transmitted to the head of the rail, supposing the train to be moving away 10 from the observer in the direction of the arrow *a* in Fig. 1, the rail 10 being the right hand rail, the tendency is to spread the rail on the direction of the arrow *b*, Fig. 1, the overturning strain tending to tip the head of 15 the rail outward, the result of the lateral strain being to exert a shearing action on the spike 40 on the right and the result of the overturning strain being to cause the outer edge of the flange of the rail to act as a fulcrum and the inner edge of the flange of the rail to tend to rise and draw the spike 40 on 20 the left of Fig. 4, the lateral strain being also resisted by the spike 40 on the right hand side, directly, and indirectly, through the plate 20 by the spike 41 on the right. Such strain is further resisted by the spikes 40 and 25 41 on the left acting through the medium of plate 30 and its lip flange 37.

The overturning strain is resisted by the 30 lip flange 27 of the plate 20 and the spike 40 on the left hand side. The lip flange 27 of the plate 20 is subjected to the overturning strain only, in the tendency of such strain to raise the inner edge of the flange of the rail, 35 the lateral strain having no effect whatever upon it. On the other hand the lip flange 37 of the plate 30 has both the overturning and lateral strain exerted upon it, the lateral strain being resisted by the spikes 40 and 41 40 on the left holding the plate 30 and its lip flange 37, its upright flange 35 at the same time supporting the web 11 of the rail against such overturning strain. Both plates exert a shearing stress upon their 45 spikes, but in different directions, and since the left plate 30 is bound in place by the load there is no upward thrust on the inner spikes and the force is distributed among the spikes on both sides of the rail. The spikes 40 do 50 substantially the same work as they do in the ordinary construction when no chair is employed and the spikes 41 supplement this work efficiently. It will be noted that the plate 20 is subjected to lifting or overturning 55 strains and that the plate 30 is subjected to both overturning and tensile strains. This enables the two plates, if deemed desirable, to be manufactured of different materials. It will also be noted that each plate is fastened on one side of the rail only and on that 60 side which is opposite its reverted flange adapted to engage the flange of the rail; and furthermore that the horizontal lock by 65 which lateral horizontal displacement of the plates is adapted to be prevented is beneath

the rail and its efficiency is increased by the weight thereof.

What I claim as new is:—

1. A rail chair comprising two plates each provided with a reverted flange adapted to 70 embrace the rail flange, one of said plates arranged with relation to the rail so as to be subjected to overturning strains and the other arranged with reference to the rail so as to be subjected to tensile strains, in combination with means integral with each plate 75 adapted to prevent their relative horizontal displacement transversely of the rail when placed adjacent to each other, comprising a tongue on one plate extending in the direction of the length of the rail and two tongues on the other plate between which said longitudinal tongue rests. 80

2. A rail chair comprising two plates each provided with a reverted flange adapted to 85 embrace the rail flange, one of said plates arranged with relation to the rail so as to be subjected to overturning strains and the other arranged with reference to the rail so as to be subjected to tensile strains, in combination with means integral with each plate 90 adapted to prevent their relative horizontal displacement transversely of the rail when placed adjacent to each other comprising a tongue on one plate parallel with the rail and 95 adapted to fit a groove on the other plate, both locking beneath the rail.

3. A plate for a rail chair comprising a base 21 having a projecting tongue extending longitudinally of the rail on which the 100 rail is to rest when in position and provided with a plurality of fastening apertures on one side of the rail and a reverted lip flange on the other side of the rail.

4. A plate for a rail chair comprising a 105 base 21 on which the rail is adapted to rest and provided with a plurality of fastening apertures on one side of the rail and a reverted lip flange on the other side of the rail and, with a projecting tongue extending 110 longitudinally of the rail upon which the rail is adapted to rest when in position, in combination with a second plate also comprising a base on which the rail is adapted to rest alongside of the first plate and provided 115 with a plurality of fastening apertures on the side of the rail opposite from those of its companion plate, a reverted lip flange on the side of the rail opposite its fastening apertures and two tongues between which the 120 tongue of the first plate rests.

5. A rail chair comprising two plates 125 locked against movement with relation to each other transversely of the rail, one of said plates being provided with a recess, a flange on one plate embracing the inner edge of the rail flange and resting on the other plate, and a flange on the other plate embracing the outer edge of the rail flange and forming a tongue to enter the recess in the first plate. 130

6. A rail chair comprising two plates locked against movement with relation to each other transversely of the rail, one of said plates being provided with a recess, a flange on one plate embracing the inner edge of the rail flange and resting on the other plate, and a flange on the other plate embracing the outer edge of the rail flange and forming a tongue to enter the recess in the first plate and provided with a vertical extension bearing against the web of the rail. 10
In testimony whereof I affix my signature in presence of two witnesses.
